TIMING MECHANISM

Noël M. Seeburg, Chicago, Ill.

Application December 31, 1931, Serial No. 584,131

20 Claims. (Cl. 194—74)

My invention pertains to timing mechanisms and is more particularly concerned with, but not limited to, a coin controlled timing mechanism for regulating the supply of electric current to an electric refrigerator, radio, phonograph, or any other mechanism operated by electric current.

An object of my invention is to provide a new and improved timing mechanism.

10 Another object is to provide new and improved coin controlled mechanism.

Another object is to provide a coin controlled timing mechanism in which the period of operation permitted by a single coin may be easily 15 changed.

Another object is to provide a coin controlled timing mechanism in which a plurality of coins may be deposited at one time, whereupon the timing mechanism will continue to supply current to the electrical apparatus operated thereby for a number of predetermined periods, corresponding to the number of coins deposited.

Another object is to provide means for indicating the number of periods which the machine 25 will continue to run without the insertion of additional coins.

Another object of my invention is to provide a coin controlled timing mechanism which will operate a special signal at any desired predetermined time prior to the expiration of the last coin on deposit in the mechanism.

Another object is to provide means for adjusting the signal without disassembling the timing mechanism.

35 Another object is to provide a coin controlled timing mechanism having a removable bank for receiving the coins deposited in the mechanism.

Another object is to provide a coin controlled timing mechanism which is rendered inoperative 40 when the bank is removed.

Another object is to provide a coin controlled timing mechanism which is simple and compact in construction, economical to manufacture, and reliable in use.

45 Another object is to provide a coin controlled timing mechanism mounted in a simple and attractive box which protects certain vital parts of the mechanism against tampering but permits an authorized service man to make necessary adjustments with ease.

Other objects and advantages will become apparent as the description proceeds.

In the drawings,—

55 Fig. 1 is a perspective view of one embodiment of my new and improved timing mechanism;

Fig. 2 is a vertical section through the embodiment of my timing mechanism shown in Fig. 1 and is taken on the line 2—2 of Fig. 6;

Fig. 3 is a fragmentary view showing a front elevation of the coin recording and switch controlling mechanism. In this view part of one ratchet wheels is broken away for the purpose of illustrating more clearly the structure of this mechanism;

Fig. 4 is an enlarged vertical section taken on the line 4—4 of Fig. 3;

Fig. 5 is a fragmentary view showing the manner in which the number of coins on deposit and still available is indicated;

Fig. 6 is a horizontal section through the embodiment shown in Fig. 2 and is taken on the line 6—6 of Fig. 2;

Fig. 7 is an exploded view of the driving mechanism;

Fig. 8 is an elevation of one of the ratchet- 20 wheels forming part of the coin recording and switch controlling mechanism;

Fig. 9 is an elevation of the other ratchet- 25 wheel forming part of the coin recording and switch controlling mechanism;

Fig. 10 is a partial vertical section through a modified form of the device wherein a removable bank is used as a coin receiver. This figure corresponds generally to Fig. 3 of the previous embodiment and illustrates the connection between 30 the coin recording and switch controlling mechanism and the door through which the bank is removed;

Fig. 11 is a partial vertical section corresponding generally to Fig. 2 showing the previous embodiment. This Fig. 11 illustrates the relationship between the bank and coin chute and the bank controlled latch for preventing insertion 35 of coins while the bank is removed;

Fig. 12 is a vertical section taken on the line 40 12—12 of Fig. 11;

Fig. 13 is a horizontal section illustrating the modified switch mechanism of this embodiment, the switch mechanism being modified to operate 45 a signal light at any predetermined period prior to the expiration of the last coin on deposit;

Fig. 14 is a fragmentary section taken on the line 14—14 of Fig. 10, illustrating the control means for the signal light;

Fig. 15 is a fragmentary section taken on the line 15—15 of Fig. 10, illustrating one means for determining the duration of the period which corresponds to a coin deposited in the mechanism;

Fig. 16 illustrates mechanism whereby prede- 55

terminated periods of any desired duration may be easily obtained;

Fig. 17 is an enlarged view of the wheel shown at the bottom of Fig. 16; and

5 Fig. 18 is a wiring diagram of the embodiment shown in Figs. 10 to 15, inclusive.

10 Referring to the drawings and more particularly to the embodiment shown in Figs. 1 to 9, inclusive, I have illustrated an embodiment of my invention wherein the mechanism thereof is compactly mounted in a suitable box 20 which is provided with an attractive appearance. The top of the box carries a plate 21 having an opening 22 for receiving coins to be deposited in the machine. A slide 23 projects through the plate 21 and has a built-over upper end adapted to be engaged by the operator's finger, whereupon the slide 23 is reciprocated to force the coin into the mechanism. The front of the box is provided 15 with a window 24 through which the mechanism for indicating the number of coins on deposit may be viewed.

20 Extending from the box 20 is an electrical conduit means 25 having a two-pronged socket 26 of ordinary construction which is adapted to be connected with the house wiring system of a building or any other suitable source of electrical supply. A second electrical conduit means 27 extends from the box 20 and is intended for connection to the electric refrigerator, radio, phonograph, washing machine, or other electrical device whose supply of current is controlled by the timing mechanism.

25 This conduit means 27 may be either permanently connected with suitable contacts on the electric refrigerator or other device, or may be provided with a plug 28 of special design adapted for removable association with a cooperating socket of similar special design forming part of the electrical circuit of the electric refrigerator or other controlled device. Such use of a special plug and socket between the timing mechanism contained in the box 20 and the controlled device makes it impossible to connect the controlled device directly with the power line of the building.

30 As best shown in Fig. 2, the coin chute 29 leads from the slot 22 downwardly to a receiving compartment 30 which comprises a partitioned off corner of the box 20 and which is lined with felt or other suitable material 31 to deaden the noise of the coins made as they are deposited therein. When a coin is inserted into the slot 22, it falls downwardly in the coin chute 29 until it reaches the position indicated in dotted lines at 32, where 35 its downward movement is arrested by one end of a lever 33. After the operator inserts each coin, he depresses the slide 23 which is held in its upward position by spring 34, thereby causing the lower end of the slide 23 to engage the coin 40 and force it past the end of the lever 33 and into the coin receiving compartment 30.

45 The lever 33 is pivoted at 35 on a partition 36 and is rigidly connected with a double ended pawl 37 which is normally held against a stop 38 by the spring 39 which acts on the end of lever 33. As the coin is forced downwardly past the end of the lever 33, the spring 39 yields and permits the lever 33 to be moved about its pivot 35. This movement of the lever 33 gives a corresponding movement to the double ended pawl 37 and causes this pawl to advance the ratchet-wheel 40 one tooth in the direction of the arrow 41 (Fig. 3).

50 The ratchet-wheel 40 is illustrated in Figs. 3, 4, 6 and 9, the latter figure showing the opposite

5 side from that shown in Fig. 3. This ratchet-wheel is rotatably mounted on an axially slidable shaft 42 carried in a sleeve 43 supported by a bracket 44 attached to the partition 36. The end 45 of the shaft 42 is enlarged and controls the 10 position of a switch lever 46 pivoted at 47 (Fig. 6) and held against enlargement 45 by a spring 48. The sleeve 43 rotatably supports a cooperating ratchet-wheel 49 shown most fully in Fig. 8. The ratchet-wheel 40 is provided with a stop 50 which 15 is adapted to engage with the stop 51 on ratchet-wheel 49 when the ratchet-wheels 40 and 49 are in one extreme of their relative positions, and to engage with the stop 52 when the ratchet-wheels 40 and 49 are in the other extreme of their relative 20 positions.

25 Each ratchet-wheel carries a separating lug 53 having a substantially hemispherical head, as shown in Fig. 4. When no coins are on deposit, the ratchet-wheel 40 and 49 are so positioned 20 that the lugs 53 engage, whereupon the ratchet-wheels are held in separated relation and switch lever 46 is moved to the position shown in Fig. 6, in which position the contacts 54 and 55 are separated and the circuit leading to the electric refrigerator or other controlled device is broken. In this position of the ratchet-wheels, the opening 56 in ratchet-wheel 40 registers either with the zero or the blank space 57 on ratchet-wheel 49, and either the zero or blank space 57 is thereupon 30 visible through the window 24.

35 The ratchet-wheel 49 rotates in the same direction as the ratchet-wheel 40 and is advanced by a pawl 58 pivoted at 59 to the partition 36. The pawl 58 is held in the position shown in Fig. 3 of 35 the drawings by a spring 60 and is moved to its other extreme position against the tension of the spring 60 by a finger 61 rotated by a shaft 62. The pawl 58 has a pin 63 which projects through a suitable opening in the partition 36 so that the 40 pawl may be manually operated for initial setting of the mechanism.

45 The shaft 62 is rotated at a predetermined speed by suitable mechanism which will presently be described, and in this embodiment of my invention one rotation of this shaft corresponds to the period of time during which the contacts 54 and 55 are maintained closed for each coin deposited in the mechanism. In the illustrated embodiment the mechanism is designed to receive quarters and to maintain the contacts 54 and 55 closed for a period of twenty-four hours for each quarter deposited in the mechanism. This means that the shaft 62 is rotated once every twenty-four hours. This shaft may be driven by any 55 suitable timing mechanism, and in the illustrated embodiment I have shown this timing mechanism as comprising an ordinary electric clock, indicated generally by the reference character 64, suitably mounted in the lower part of the box 20. This 60 electric clock includes a self-starting sub-synchronous motor 65 having leads 66 and 67 connected to terminals 68 and 69 mounted on a suitable panel 70 supported in the upper part of the 65 box 20. To the terminals 68 and 69 are connected the two wires which together form the supply conduit 25. The motor 65 drives suitable reduction gearing diagrammatically illustrated in Fig. 7, and this reduction gearing in 70 turn drives the shaft 62 at such speed that this shaft rotates once for every twenty-four hours. The clockwork mechanism 64 includes a hand wheel 71 which may be utilized to set the finger 61 against the right-hand edge of the pawl 58,

75 75

as viewed in Fig. 3, as the initial position for the mechanism.

Where the shaft 62 rotates once every twenty-four hours, the electric refrigerator or other controlled device will operate one day for each quarter deposited, and thus the number on ratchet-wheel 49, which is visible through window 24 and opening 56 in ratchet-wheel 40, indicates the number of days which the electric refrigerator or other controlled device will operate without the deposit of additional coins, and a suitable sticker stating this fact may be pasted on the window 24, as indicated in Fig. 5 of the drawings. Since this dial, in reality, indicates the number of unused coins on deposit in the mechanism, it is obvious that if the shaft 62 be made to rotate at a different speed, the dial will not indicate the number of days which the electric refrigerator or other controlled device will continue to operate without the deposit of additional coins. Such periods may, of course, be either longer or shorter than twenty-four hours.

Referring particularly to Figs. 2 and 6, it will be seen that contact 55 is connected by a wire 71 with terminal 69, and contact 54 is connected by a wire 72 with a terminal 73. A fourth terminal 74 is connected with terminal 68 by a strip 75 of metal or other suitable conducting material. Two terminals 73 and 74 are connected to the wires leading to the electric refrigerator or other controlled device. As shown in Fig. 1, these wires together form the flexible conduit 27.

The wires which form the conduits 25 and 26 pass through suitable openings provided in the bottom of the box 20 and these openings are insulated by rubber bushings 76. From thence the wires are led to a retaining clip 77 and pass out through an opening 78 provided in the rear wall of the box adjacent the bottom thereof. The box 20 is provided with suitable rubber feet 79 which permit the box to be placed upon a finished surface without fear that the box will scratch such surface.

The rear of the box is closed by a cover 80 provided with fingers 81 which fit into suitable slots provided in the bottom of the box. The upper central portion of the cover is perforated to pass over a threaded pin 82 onto which is screwed a nut 83. Near its outer end the pin 82 is provided with a cross bore, through which may be passed a wire 84 which can be sealed as indicated at 85.

The operation of the embodiment of my timing mechanism which I have just described is as follows: The cover 80 is removed and the mechanism set in the starting position, with the dial showing "0", and the finger 61 just past the snap-over position of the lever 58. If the operator finds that the dial shows "1", he can set the mechanism in starting position by simply turning the handwheel 71 in a clockwise direction, as viewed in Fig. 2, until the finger 61 snaps past the lever 58. This will cause the dial to indicate "0" and will place the finger 61 in proper starting position. If the dial originally indicated a number larger than "1", it can be brought to a position where it indicates "1" by pushing on the pin 63 and allowing the spring 60 to snap the lever 58 back to its normal position.

If the dial originally indicated either "0" or

the blank marked by the reference numeral 57 in Fig. 8, the best practice would be for the operator to pass sufficient coins through the mechanism to cause the dial to indicate "1" and then set the mechanism as previously described. Having set the mechanism to starting position, the operator places the cover 80 in position and secures it by means of the nut 83. He then locks the cover and nut in place by passing a wire 84 through the hole in the pin 82 and seals the ends of the wire. He then connects the plug 26 with a socket which forms part of an electrical circuit which supplies current of the proper voltage and frequency, and he then connects the plug 28 with the special socket provided on the electric refrigerator or other electrical device whose source of current is to be controlled. The timing mechanism is then ready for use by the purchaser, renter or other user of the electric refrigerator or other controlled device.

As soon as the plug 26 is connected to the power line, the electric motor 65 starts, and if the user is to obtain the full twenty-four hour period for his first quarter, he should drop this quarter immediately into the slot 22. The quarter comes to rest in the position indicated by the reference numeral 32 (Fig. 2) and the user thereupon pushes down on the slide 23 which forces the quarter past the end of the lever 33 and into the coin receptacle 30. The lever 33 is rotated about its pivot 35 and causes the pawl 37 to advance the ratchet-wheel 40 one notch in the direction of the arrow 41. This advancement of the ratchet-wheel 40 moves lugs 53 out of engagement with each other and permits spring 48 attached to switch lever 46 to move the switch lever in a clockwise direction, as shown in Fig. 6, thus bringing contacts 54 and 55 into engagement and closing the circuit leading to the electric refrigerator or other controlled device.

This same movement of switch lever 46 moves shaft 43 to the left, as viewed in Fig. 4, and moves ratchet-wheels 40 and 49 closer together. This advancement of ratchet-wheel 40 also shifts opening 56 so that it exposes the numeral "1" on ratchet-wheel 49. If additional coins be deposited, the ratchet-wheel 40 will be advanced one notch for each coin deposited, until the dial indicates "22", whereupon pin 50 will come into engagement with pin 52 and prevent further rotation of ratchet-wheel 40. If, now, a twenty-third coin be deposited, the lever 33 and pawl 37 will oscillate idly to permit depositing of the coin but will not serve to advance the ratchet-wheel 40.

As the first twenty-four hours of operation draw to a close, the finger 61 reaches the position shown in Fig. 7 where it engages the lever 58 and moves the lower end of the lever 58 to the right, as viewed in Figs. 3 and 7. When the lower end of lever 58 has reached its extreme right-hand position, the finger 61 moves therewith and permits the spring 60 to snap lever 58 back to its normal position, thereby causing pawl 59 to advance ratchet-wheel 49 one notch in the direction of the arrow 41. If a single coin has been deposited, this advancement of ratchet-wheel 49 causes lugs 53 to reengage and separate ratchet-wheels 40 and 49, thereby moving switch lever 46 against the tension of its spring 48 and separating contacts 54 and 55, thus breaking the circuit leading to the electric refrigerator or other controlled device. The motor 65 continues to run and if another coin is not deposited within twenty-four hours after sepa- 75

rating of the contacts 54 and 55, the finger 61 again engages lever 58 to advance ratchet-wheel 49 until pin 50 engages pin 51. This last advancement is not a complete notch but is sufficient to permit finger 61 to slip past the end of lever 58. In this position the dial indicates the blank space represented by the reference character 57.

If no more coins are deposited, the motor 65 continues to run and the finger 61 slips past the end of lever 58 once every twenty-four hours without, however, causing any further movement of the ratchet-wheels. In this position the lugs 53 continue to engage each other and maintain the ratchet-wheels separated and the contacts 54 and 55 likewise separated.

If the user permits the mechanism to reach this position, he is penalized one coin since the first coin deposited will simply move the ratchet-wheels to the "0" position and will not close contacts 54 and 55, but another coin must be deposited to advance the ratchet-wheels to a position where the dial indicates "1", in which position the contacts 54 and 55 are brought into engagement with each other.

If more than one coin was deposited, the contacts 54 and 55 will not be separated upon the expiration of the first twenty-four hour period but will remain closed for as many periods as there were coins deposited. One important advantage of my mechanism is that additional coins may be deposited at any time without interfering with the operation of the mechanism, and full value will be received for each coin deposited, provided no more than twenty-two coins are deposited at any one time. Another important advantage is that the motor 65 continues to operate, even when all coins deposited have been used, and thus this motor is not subjected to the heavy loads and wear and tear attendant upon frequent stopping and restarting.

At periodic intervals the operator takes off the cover 80 and removes the coins from the coin receptacle 30. If a slug or mutilated coin should become stuck in the coin chute, a tool can be inserted through slot 86 or slot 87 and the slug or mutilated coin forced out of the coin chute. It should be noted that the cover 80 may be removed and the mechanism inspected and coins taken out of the receptacle 30 without interfering in any way with the operation of my new and improved timing mechanism.

Timing mechanisms of the class described in this application are commonly used as a means for selling electric refrigerators and other electric devices. In selling an electric refrigerator a timing mechanism is supplied with each refrigerator and the householder purchases the refrigerator by depositing a coin each day in the timing mechanism or by depositing a plurality of coins at periodic intervals. The usual practice is to sell the small type household electric refrigerator on the basis of twenty-five cents per day, which means that at the end of each month there should be approximately \$7.50 in coins in the coin receptacle 30. An operator or agent is sent around once a month to collect the coins from the coin receptacles of the timing mechanisms.

It frequently happens that the operator or agent must call several times at each household in order to obtain the coins in the coin receptacle of the timing mechanism, and the expense of making such collections is accordingly very high. I have devised a way of eliminating the expense of and necessity for such collections.

In the form of my invention illustrated in Figs. 10 to 15, inclusive, I have shown a timing mechanism which is provided with a bank for receiving the coins deposited in the mechanism. This bank cannot be opened by the householder but must be brought by the householder at least once each month to the store from which he is purchasing the electric refrigerator or other electric device. The store will open the bank, remove the coins, and return the bank to the householder, or in some cases may find it more expedient simply to exchange the bank turned in by the householder for an empty bank which the householder can take home and insert in the timing mechanism. This has the advantage that it makes unnecessary the employment of collectors or agents and further serves to bring the householder into the store where he may see other articles which he desires to purchase.

Referring particularly to Figs. 10 to 12, inclusive, I have illustrated a box 20' which is substantially identical with the box 20 of the previously described embodiment. The box 20' provides a space 30' for receiving a bank 88 which may be of any suitable construction and may be of the type commonly supplied in the form of small savings banks given to the customers of banking institutions. Such savings banks are usually provided with a lock which can only be opened by the key which is retained by the banking institution. The bank 88 is provided with openings 89 into which project pins 90 carried by a partition 91. The purpose of these pins and openings is to require the householder to place the bank in the space 30' in the proper position. When the bank is properly located in the space 30', the coin receiving slot 92 in the upper part of the bank registers with the lower end of the coin chute 93, which may be identical in all essential respects with the coin chute in the embodiment previously described.

The upper rear corner of the bank 88 is preferably beveled as indicated at 94, and when the bank is inserted into the space 30' this beveled corner 94 engages the cam-shaped lower end 95 of a slideable member 96 which is guided by pins 97 attached to the coin chute. The spring 98 forces the diagonal portion 99 of the member 96 against the out-turned end of a part 100. When the slideable member 96 is in the raised position shown in Figs. 11 and 12, the finger 101, formed integrally with the upper end of the slideable member 96, has its end resting in a slot 102 formed in one side of the coin chute. The end of the finger 101, however, does not project across the coin chute so as to interfere with the insertion of coins thereinto. When the bank 88 is removed, spring 103 moves slideable member 96 downwardly, whereupon finger 101 moves to the right, as viewed in Fig. 12, until it extends across the coin chute and prevents the insertion of coins thereinto.

The bank 88 is inserted and removed through a door 104 which is pivoted to the box 20' at 105. The door 104 may be provided with a handle or knob 106 and is held in closed position by a spring lock indicated at 107. The door carries a projection 108 which, in the closed position of the door, holds the lock member 109 in elevated position, as indicated in Fig. 10 of the drawings. The lock member 109 is an L-shaped strip of metal which is guided for vertical sliding movement by pins 110 attached to the box 20'. When the door is opened the lock member 109 is moved downwardly by spring 111, whereupon the end 75

112 of lock member 109 engages the teeth of ratchet-wheel 113 and prevents pawl 37 from advancing this ratchet-wheel if an attempt were made to deposit a coin in the mechanism while 5 the door is open. This arrangement makes it impossible for a user to insert his hand or a tool through the open door and hold the slideable member 96 elevated while he deposits coins in the mechanism.

10 The bank 88 is preferably provided with a handle 114 which facilitates removal of the bank and also is of such length that the mere act of closing the door 104 locates the bank in proper position. The pins 90 make it impossible to 15 properly place the bank in the space 30'.

Under certain circumstances I have found it desirable to give a warning signal a predetermined time before the expiration of all of the coins on deposit in the mechanism. In this embodiment of the invention I have shown this warning as a light 115 which is located just behind a glass disk 116 covering an opening in the front plate 117. The light 115 may be red or any other suitable color, and the glass disk 116 20 may be made removable so that the light bulb may be replaced when necessary. The light bulb is supported in a socket carried by a tubular support 118 attached to the cover plate 117.

The light is supplied with current through a 30 flexible cable 119 composed of two wires, one of which leads directly to the terminal 68 which is connected to one side of the supply line 27. The other wire is connected to a terminal 120 in electrical connection with a resiliently supported 35 contact 121 which is adapted to form an electrical connection with a cooperating contact 122 associated with a terminal 123 connected by the wire 71 with the terminal 69 to which is attached the other side of the supply line 27. In this instance the current to the electric refrigerator or other electrical device is controlled by contacts 54' and 55, the contact 54' having limited movement and being urged toward the contact 55 by a spring 124. Outward movement under the action of spring 124 is limited by engagement of the end 125 of cylindrical member 126 with the enlarged head of contact 54'. Wire 72 connects contact 54' with terminal 73.

In this embodiment ratchet-wheels 113 and 50 127 are first partially separated to move switch lever 46 in a counter-clockwise direction about its pivot 47 and thereby engage contacts 121 and 122 to light the light 115 and thus give warning that the coins on deposit will be exhausted 55 upon expiration of a predetermined period which may bear any desired relationship to the period of time which corresponds to a single coin. This movement of switch lever 46 does not disengage contacts 54' and 55 since contact 54' is urged against contact 55 by spring 124 and thus follows the movement of switch lever 46. When the coins are exhausted the ratchet-wheels 113 and 127 are given an additional separation which moves switch lever 46 an additional amount in a counter-clockwise direction about its pivot 47 and causes separation of contacts 54' and 55. Resiliently mounted contact 121 yields sufficiently to accommodate this additional movement of switch lever 46 and contacts 121 and 122 remain 60 engaged.

The means for giving the partial separation of ratchet-wheels 113 and 127, which results in lighting of the warning light 115, is shown most clearly in Fig. 14. In this embodiment ratchet-wheel 113 is provided with a series of threaded

openings 128 into which may be screwed signal pins 129. The threaded openings 128 are arranged along an arc which passes through the axis of the lug 53 carried by the ratchet-wheel 113. The axis for this arc is the axis of the 5 ratchet-wheel 113. The signal pins 129 have inner ends which project far enough to engage the lug 53 carried by ratchet-wheel 127 and cause enough separation of the ratchet-wheels to close contacts 121 and 122 and thereby light signal 10 light 115.

The signal pins 129 are made so that they can be inserted into threaded openings 128 by simply removing window 24 or, if preferred, the front plate 117 may be made removable. The threaded openings 128 are so spaced that each threaded opening controls the same angular movement of the ratchet-wheel which is controlled by one of the notches thereof. If one signal pin be inserted in the threaded opening nearest to the 20 lug 53 carried by the ratchet-wheel 113, the signal will light when there is only one unused coin on deposit and will continue lighted until sufficient coins are deposited so that more than one unused coin is on deposit in the mechanism. 25 If two signal pins be inserted, as shown in Fig. 14, the signal will light when only two unused coins remain in the mechanism and will continue lighted until enough coins are deposited so that the unused coins on deposit exceed two. 30

When a larger and more expensive electric refrigerator or other electrical device is sold, it may be desired to require the deposit of two or more quarters for each 24 hours; in other words, to reduce the period per coin from 24 hours to 35 12 hours or 6 hours or some other lesser interval of time. It is not always convenient or desirable to do this by changing the gearing of the clock-work mechanism. I therefore show, in Figs. 10 and 15 of the drawings, a very convenient way of 40 accomplishing this result and of providing a mechanism in which the period of operation corresponding to a single coin may be easily changed. In this embodiment I have shown the shaft 62 as carrying a pin wheel 63' having 45 threaded openings 130 provided with any desired number of threaded openings 131 into which may be screwed removable pins 132.

If the shaft 62 is rotating once every 24 hours and it is desired that the period of operation for 50 each coin shall be 24 hours, a single pin is inserted in one of the threaded openings 131. If, however, a more expensive electric refrigerator is being purchased, it may be desired to require the purchaser to deposit two quarters each day, 55 in which case two pins 132 would be inserted in diametrically opposite openings. Where a still more expensive refrigerator or other device is being purchased, it may be desired to require the purchaser to pay a dollar a day, which would 60 mean four quarters. In this case all four of the openings shown in Fig. 10 would be filled with pins 132. It is obvious that any desired number of openings may be provided and that the number and arrangement of pins may be changed 65 as desired.

The tapered ends of the pins 132 project sufficiently to engage the lever 58 which is located behind the wheel 130, as viewed in Fig. 10. The front plate 117 is shown as provided with fingers 70 133 similar to the fingers 81 carried by the cover 80, and the front plate 117 is secured in place in the same manner in which the cover 80 is secured in place.

In some instances it is desired to make the pe- 75

riod of operation corresponding to a single coin, 15 hours or some other period which is not evenly divisible into 24 hours. I accomplish this by the mechanism shown in Figs. 16 and 17. On shaft 5 62 I mount a pin wheel 134 which may be provided with any desired number and arrangement of threaded openings 135. In the particular wheel shown I have provided a series of 8 equally spaced threaded openings and also a series of 10 equally spaced threaded openings into which may be threaded pins 132. With this arrangement of openings I can provide the wheel 134 with either a single pin or with 2, 4, 5, 8 or 10 equally spaced pins. The pins in the wheel 15 134 actuate a pawl 136 pivoted at 137 on the partition 36. The pawl 136 is moved in the opposite direction by a spring 138 and rotates a ratchet-wheel 139 carrying pins 140 which may or may not be made removable. The pins 140 20 in turn actuate a pawl 141 pivoted at 142 to the partition 36. The pawl 141 rotates ratchet-wheel 49.

In Fig. 16 I have shown wheel 134 as provided with 5 equally spaced pins 132 so that pawl 136 25 will be operated 5 times for each rotation of shaft 62 or 5 times for each 24 hours. Each operation of pawl 136 advances ratchet-wheel 139 one tooth or one-third of the distance between successive pins 140. Each pin 140 causes pawl 141 30 to advance ratchet-wheel 49 one notch which neutralizes the one notch advancement of ratchet-wheel 40 which occurs when a coin is deposited in the mechanism. With this particular arrangement the period corresponding to each coin 35 deposited is 3 times 24, divided by 5, or 14½ hours which corresponds approximately to a payment of \$12.00 a month. By a proper arrangement of the pins 132 and 140, payments approximating \$18.00 a month, and similar irregular sums, can 40 readily be obtained.

In Fig. 18 I have shown a wiring diagram of that embodiment which incorporates the signal light 115. In this wiring diagram I have indicated the A. C. supply line as provided with a 45 switch 142 which is outside of my timing mechanism and may be considered as the switch usually located in the basement of a dwelling. In this diagram the motor of the clock mechanism 64 is illustrated as directly connected across the 50 A. C. line, whereas the electric refrigerator or other controlled unit is connected across the A. C. line through contacts 54 and 55. The signal light 115 is connected across the A. C. line through contacts 121 and 122.

In the several embodiments of my invention 55 all of the operating mechanism, including the coin chute, clock-work mechanism, ratchet mechanism, and switch mechanism, is mounted on the partition 36. This partition is removably attached to brackets 143 and 144 by screws 145. The brackets 143 and 144 are spot-welded or otherwise attached to the ends of the box 20. This arrangement makes it possible to assemble 60 all of the operating mechanism with the exception of the slide 23 on the partition 36 before it is placed in the box 20, and after everything has been assembled on the partition 36 and all necessary adjustments have been made, the partition may be inserted in the box 20 and secured there- 65 to by screws 145. Thereafter slide 23 is placed in position and connected with the lower end of spring 34 which completes the assembling of the mechanism except for the application of the rear cover 80 which may be secured to the box as 70 previously described. The partition 36 may be 75

readily removed for inspection and adjustment of the various parts of the mechanism.

While I have disclosed several embodiments of my invention, it is to be understood that my invention is not limited to the specific embodiments shown but may be incorporated in numerous other forms, and that the scope of my invention is limited solely by the following claims.

I claim:

1. In mechanism of the class described, the combination of a first ratchet-wheel, a second ratchet-wheel coaxial therewith, separate means for advancing said ratchet-wheels, one of said ratchet-wheels having an opening therethrough, and indicating means carried by the other ratchet-wheel and adapted to be exposed through said opening.

2. In mechanism of the class described, a pair of rotatable ratchet-wheels, means for separating said wheels when in one position, means for moving said wheels to a second position, means for bringing said wheels together, a switch operated in one direction by the separating movement of said wheels and in the opposite direction when said wheels are brought together, and means for indicating the position of said wheels.

3. In mechanism of the class described, a switch, ratchet mechanism for operating said switch, a pawl for actuating said ratchet mechanism, a shaft, means for driving said shaft at a predetermined speed, a wheel carried by said shaft, a pin projecting from said wheel to engage said pawl, and means for removably supporting said pin in said wheel.

4. In mechanism of the class described, the combination of a box, a switch mounted therein, ratchet mechanism for actuating said switch mounted in said box, mechanism in said box for driving a shaft at a predetermined speed, a disk mounted on said shaft, said disk having threaded 40 openings therein at spaced intervals, pins removably mounted in said disk, said pins projecting from one face thereof, and a pawl for actuating said ratchet mechanism actuated by said pins.

5. In mechanism of the class described, the combination of a box, a switch mounted therein, clock-work mechanism for driving a shaft at a predetermined speed, coin controlled mechanism for closing said switch, said coin controlled mechanism having a part extending outside of said box, and means connecting said shaft with said switch to open said switch, said last-named means including a pawl, a disk mounted on said shaft and rotatable therewith, said disk located in said box, a pin carried by said disk, said pin projecting from said disk to engage said pawl, means interconnecting said pin and said disk to permit insertion of said pin without removing said disk from said box, and a removable plate 60 for said box.

6. In mechanism of the class described, the combination of a ratchet-wheel, a second ratchet-wheel, means for separating said ratchet-wheels a given distance, a switch actuated upon such separation of said ratchet-wheels, means for separating said ratchet-wheels a greater distance, and a second switch operated by such greater separation of said ratchet-wheels.

7. In mechanism of the class described, the combination of two ratchet-wheels in axial alignment, a lug for giving said wheels a partial separation, a second lug for giving said wheels a greater separation, means for relatively rotating 70

said ratchet-wheels, and mechanism operated by each of said separations.

8. In mechanism of the class described, the combination of a pair of ratchet-wheels, a large lug carried by each of said wheels, said wheels being separated by engagement of said lugs, a second lug carried by one of said wheels for causing the lesser separation of said wheels, means for relatively rotating said ratchet-wheels, 10 and mechanism operated by separation of said wheels.

9. In mechanism of the class described, a ratchet-wheel, a lug carried thereby, a second ratchet-wheel, a lug carried by said second ratchet-wheel, switch means operated by engagement of said lugs, a pin removably mounted on one of said wheels, other switch means operated by engagement of said pin with one of said lugs, and means for relatively rotating said ratchet- 20 wheels.

10. In mechanism of the class described, the combination of a box, a coin chute extending thereto, a slot for inserting coins into said chute mechanism actuated by the passage of a coin through said chute, a removable bank for receiving said coin and means engaging the bank for preventing the insertion of a coin through said slot and for rendering said mechanism inoperative when said bank is removed.

30 11. In mechanism of the class described, the combination of a box, a coin chute therein, means actuated by passage of a coin through said chute, a receiver for coins that have passed through said chute, means for closing said chute, and a connection between said last-named means and said receiver whereby said chute is closed when said receiver is out of place.

12. In mechanism of the class described, the combination of a switch, ratchet mechanism for operating said switch, coin controlled means for operating said ratchet mechanism, an enclosed bank adapted to receive coins, timing means for operating said ratchet mechanism, a latch normally tending to render said ratchet mechanism inoperative, and means enclosing said bank adapted to hold said latch in unlatched position.

45 13. In mechanism of the class described, the combination of a switch, ratchet mechanism for actuating said switch, coin controlled means for operating said ratchet mechanism, an enclosed bank adapted to receive coins, timing means for operating said ratchet mechanism, a lock normally tending to render said coin controlled means inoperative, and means enclosing said bank adapted to hold said lock in non-locking position.

50 14. In mechanism of the class described, the combination of a box, a switch supported therein, ratchet mechanism controlling said switch, coin controlled means for operating said ratchet mechanism, an enclosed bank adapted to receive coins, timing means for operating said ratchet mechanism, operated means for rendering said ratchet mechanism inoperative, operated means for rendering said coin controlled mechanism inoperative, and means engaging said bank for rendering one of said last operated means inoperative.

55 15. In mechanism of the class described, the combination of a box, a switch supported therein, means for actuating said switch, latching

means tending to engage said actuating means to render it inoperative, a door for said box, and a connection between said door and said last-named means adapted, when the door is closed, to hold the latching means out of engagement 5 with said actuating means.

16. In mechanism of the class described, the combination of a box, a coin chute associated therewith, a part adapted to close said coin chute, a removable container for receiving coins passed 10 through said chute, a connection between said container and said part whereby said part is rendered inactive when said container is in cooperative relation to said coin chute, and means causing said part to close said coin chute to prevent the insertion of a coin when said container is removed.

17. In mechanism of the class described, a switch, a ratchet mechanism for actuating said switch, said ratchet mechanism including a 20 ratchet-wheel, a coin chute, a pawl actuated by coins passing through said chute to advance said ratchet-wheel, a lock for preventing rotation of said ratchet-wheel, a bank for receiving coins passed through said chute, said bank being removable, means for maintaining the bank in cooperative relation with said chute and means associated with last said means for rendering said lock inoperative when said means is in its bank 25 maintaining position.

30 18. In mechanism of the class described, the combination of an operated element, timing mechanism for operating said element, a variable speed drive connecting said element with said timing mechanism, said drive including a pawl, 35 a ratchet-wheel having teeth cooperating with said pawl, pins carried by said ratchet-wheel, said pins being spaced at intervals greater than the distance between successive teeth, a second pawl operated by said pins, and a second ratchet-wheel operated by said second pawl, and other means for operating said element.

35 19. In mechanism of the class described, the combination of a box, a partition therein, a switch, a motor, a coin chute, all located on one 45 side of said partition, ratchet mechanism including a dial on the other side of said partition, means connecting said coin chute, motor and switch with said ratchet mechanism, and a signal on the same side of said partition as said dial.

40 20. A coin-free timing control for cutting off electric supply after a predetermined period, comprising timing mechanism, coin-free mechanism adapted to be actuated by insertion of a plurality of coins to set the timing mechanism for operation for a number of periods depending upon the number of coins inserted, and a switch arm actuated by said timing mechanism towards and at the end of said periods, a pair of contacts adapted to cooperate with said arm, said timing mechanism being adapted to move said arm to one position to engage one contact and being adapted to move the arm to a second position to engage said second contact, the first said contact being movable towards the second, and a signal associated with said second contact and adapted to be energized near the end of said periods and at a predetermined time prior to the movement of the switch arm away from the first said contact.
